UNITED STATES PATENT OFFICE.

FREDERICK A. HIGGINS, OF WINTHROP, MASSACHUSETTS, ASSIGNOR TO
JOHN W. YORK, OF PORTLAND, MAINE.

GAME-BOARD.

SPECIFICATION forming part of Letters Patent No. 511,773, dated January 2, 1894.

Application filed March 13, 1893. Serial No. 465,685. (No model.)

To all whom it may concern:

Be it known that I, FREDERICK A. HIGGINS, a citizen of the United States, and a resident of Winthrop, in the county of Suffolk and State 5 of Massachusetts, have invented new and useful Improvements in Game-Boards, of which the following, taken in connection with the accompanying drawing, is a specification.

This invention relates to improvements in 10 game boards and it is carried out as follows, reference being had to the accompanying drawing, which represents a top plan view of the improved game board.

The invention consists of a board having a 15 central square field A divided in sixty four contrasting squares similar to a checker board and may be used for the purpose of playing chess, checkers or similar games usually played on such a board. Adjoining the four 20 sides of said checker board A are four rectangular fields B, C, D, and E, each one being of a length equal to the center field or checker board A and of any desired width. Each of the four fields B, C, D, and E are subdivided 25 in squares of a size equal to the squares in the checker board A as shown in the drawing, the shaded squares b, c, d, e, in said side fields being preferably made in contrasting colors, one relative to the other respective fields. 30 The squares b, c, d, e, are preferably numbered or marked as shown.

At the four corners of the board are the respective square fields F, G, H and I each of which is a square the side of which is equal to 35 the width of the respective rectangular fields B, C, D, E, as shown. Each of said squares F, G, H, and I is subdivided in contrasting squares equal in size to the squares in the center and side fields.

40 a, g, i, are wicket marks on the respective

fields A, G and I arranged in a manner similar to the location of wickets in croquet games as shown.

Men or checkers or disks of any well known form or design may be used in connection 45 with the game board according to the game played thereon.

What I wish to secure by Letters Patent and claim is—

1. The herein described game board consisting of a square center field A subdivided in squares, combined with the rectangular side fields B, C, D, E, and square corner fields F, G, H, and I likewise subdivided in squares of a size equal to the squares in the center field, 50 substantially as and for the purpose set forth.

2. The herein described game board consisting of a square center field A, subdivided in contrasting squares combined with rectangular subdivided side fields B, C, D, E, and 60 square sub-divided corner fields F, G, H, and I, said center and corner fields having wicket marks a, g, i arranged thereon substantially as and for the purpose set forth.

3. The herein described game board consisting of a square center field A subdivided in contrasting squares combined with rectangular subdivided side fields B, C, D, E having marks or figures on a portion of their subdivisions and square subdivided corner fields 70 F, G, H, I, substantially as and for the purpose set forth.

In testimony whereof I have signed my name to this specification, in the presence of two subscribing witnesses, on this 25th day of 75 February, A. D. 1893.

FREDERICK A. HIGGINS.
